Application June 11, 1951, Serial No. 230,986.

24 Claims. (Cl. 19—131)

1

This invention relates to textile fiber drafting mechanisms for spinning and roving frames, and more particularly to a novel textile drafting mechanism capable of drafting textile fibers of widely varying lengths and characteristics, as well as mixtures of such widely varying fibers.

In recent years it has become common for textile manufacturers to mix or blend textile fibers of various types and characteristics to produce fabrics having at least some of the advantages of the various fibers used. For example, cotton and wool mixtures are well known; as are mixtures of such natural fibers with any of the various synthetic fibers, such as rayon, nylon and the like. It has, however, been impossible in many of such mixtures to take full advantage of the properties of the various fibers, due to the difficulty of simultaneously drafting both long and short fibers, as in mixtures, since the well known apparatus for drafting long fibers, such as wool and many synthetics does not provide sufficient control for drafting short fibers such as cotton; while the equally well known apparatus for drafting short fibers cannot successfully draft long fibers due to the mechanical limitations of such apparatus, as well as the laps ups which occur when an attempt is made to draft even relatively long fibers on such apparatus. Thus, the fiber length in such mixtures has been limited and controlled by the short fibers of the mixture, and the longer fibers to be blended have generally been cut down to a length which could be drafted by the apparatus necessary for controlling the shorter fibers. Under such circumstance, not only could little advantage be taken of the benefits arising from the length of such longer fibers but, particularly in the case of cotton and synthetic fiber mixtures, it has been necessary to add a step of cutting the synthetic fibers into short lengths which could be handled on cotton machinery, thus no advantage could be taken of the most desirable length of the synthetic fibers.

Attempts have been made to solve the above-mentioned difficulties by producing a single zone drafting apparatus of the apron type having, between a pair of delivery rolls and a pair of holding rolls, a fiber control mechanism comprising an overlying roll cooperating with an endless apron to control the fibers, the endless apron generally having an apron driving roll, an apron bar within its loop, as well as a suitable tensioning roll and with the overlying roll running in a depressed curve of the apron and providing a control zone having a short yielding grip on the sliver being drafted, such an arrangement being shown in

2

Shaw U. S. Patent No. 2,588,420. In commercial use, however, such apparatus does not have the flexibility of the present apparatus in handling extreme variations in lengths and types or kinds of fibers, and mixtures thereof.

We have found that, in order to provide proper control for drafting fibers of a wide variety of lengths and other characteristics, particularly in the case of mixtures containing both short and long fibers, not only is it necessary to provide a light frictional grip for the fibers of a sliver (either twisted or untwisted as with spinning and roving frames respectively) between the apron and roll to control the short fibers while at the same time permitting the longer fibers to pass through without being firmly nipped by the control mechanism, but also it is an important advantage positively to drive the overlying apron roll and to provide a much wider range of adjustment of the drafting and control conditions as well as a far better control of the fibers than has heretofore been considered possible. For instance, in order simultaneously to draft very short and very long fibers—perhaps the most difficult situation—it is necessary that the release point of the control zone be as close to the nip of the delivery rolls as possible to control the short fibers and that the fibers be held in uniform light frictional contact controlling the short fibers while at the same time permitting the long fibers to be slip-drafted through the control zone by the delivery rolls.

We have further found that in drafting elements employing a control zone having an overlying roll running within the depressed curve of an apron in order properly to drive the apron to provide the necessary uniform light frictional control throughout the entire control zone as well as to provide a control zone having a constant release point, it is desirable to have the peripheral speed of the overlying roll slightly higher (e. g. 3-6%) than that of the apron. The usual apron drives cannot provide the necessary uniform contact around the periphery of the overlying roll since, as the frictionally driven overlying roll is travelling slower than the apron due to slippage and frequently at a non-uniform speed, the apron tends to form a non-uniform bulge away from the roll. Such a bulge in the apron not only results in a non-uniform pressure throughout the control zone, but also results in the constant shifting of the release point of the control zone, both of which cause uneven drafting. We have thus found it highly desirable positively to drive the overlying apron roll at a peripheral speed slightly

higher than that of the apron to urge the apron around the overlying roll and apron bar without forming such a bulge. Furthermore, in order to improve the uniform light frictional control throughout the control zone, we have provided a novel apron drive having relatively large apron contacting driving surfaces, as well as an apron driving nip between a pair of positively driven rolls. Such an arrangement provides, due to the large area of contact of the apron with its driving rolls, a means of driving the apron at a substantially uniform speed to give improved drafting of fibers, without the necessity of excessive apron nipping pressures.

In regard to the practical commercial requirements of drafting mechanisms capable of drafting mixtures of fibers of different lengths, although it has been suggested that a fiber control mechanism having a positively driven overlying apron roll is desirable, the prior arrangements involving positively driven top rolls have not been satisfactory since the gears used to drive the apron rolls from the long apron supporting and driving roll tended to become dirty and were extremely difficult to keep clean, as the long driving shaft had to be taken out in order properly to clean some of the elements. Replacement or cleaning of the under surfaces of a single apron was also difficult, since the driving shaft had to be taken out to do so, meanwhile stopping the entire frame. As a result of the above objections, such frames have never come into extensive use.

Accordingly, it is an object of the present invention to produce a textile drafting mechanism of the single apron type having a positively-driven overlying apron roll which is capable of successfully drafting fibers and mixtures of fibers having great variations in length and properly controlling both the short and long fibers during such drafting.

It is a further object of the invention to produce a novel apron drive which will provide a substantially uniform light frictional contact between an overlying apron roll and an apron.

It is a still further object of the present invention to produce a drafting element which may be quickly and easily adjusted to provide optimum settings for control of fibers of widely varying lengths and characteristics.

It is a still further object of the present invention to produce a drafting mechanism which may be easily and quickly disassembled without the use of tools to allow cleaning and replacement of the elements therein, and which then may be assembled without the necessity of readjusting the mechanism, the various elements automatically fitting together to give the exact former adjustment.

The nature of this invention, as well as other objects and features thereof, will be readily understood from the following description when read in connection with the accompanying drawings, in which—

Fig. 1 is a cross-sectional side elevation of the drafting mechanism of the invention;

Fig. 2 is a cross-sectional front elevation of a portion of the drafting mechanism of Fig. 1, taken on the line 2—2 of Fig. 1;

Fig. 3 is a plan view of certain portions of the drafting mechanism of Fig. 1;

Fig. 4 is a diagrammatic front elevation of the drafting mechanism of the invention;

Fig. 5 is a side elevation of a portion of the drafting mechanism of the invention;

Fig. 6 is a plan view of the portion of the drafting mechanism shown in Fig. 5;

Fig. 7 is a cross-section taken on the line 7—7 of Fig. 5;

Fig. 8 is a cross-sectional side elevation of certain portions of the drafting mechanism of the invention;

Fig. 9 is an isometric view of a portion of the drafting mechanism of the invention;

Fig. 10 shows a modified form of a portion of the drafting mechanism of the invention;

Fig. 11 is a cross-sectional view of the modification of Fig. 10;

Fig. 12 shows in cross-section a roll portion of the drafting mechanism of the invention, and

Fig. 13 shows in cross-section a modified form of a roll portion of the drafting mechanism of the invention.

Referring first to Fig. 1, the textile fiber drafting mechanism of the invention includes a pair of delivery rolls 3 and 4 at its front end and a pair of holding rolls 5 and 6 at its back end, forming between said pairs a drafting zone. The lower delivery roll 4 and the lower holding roll 6 extend for substantially the entire length of the machine and are driven in the customary manner by gearing located at the end of the spinning or roving frame. The upper delivery rolls 3 and the upper holding rolls 5 are supported and weighted by any suitable means to act on a sliver to feed and draft it, the arrangement herein generally shown being that of Fig. 6 of V. A. Burnham et al. U. S. Patent No. 2,525,647, and eminently satisfactory.

Such arrangement includes a weighting bar 7 on which said rolls 3 and 5 are mounted in bearings 8 and 9 respectively, said bearing 9 for the upper holding roll being mounted on said bar in adjustably fixed position so that, through set screw 10 therein, it may be adjusted along said bar to vary the spacing between said rolls 3 and 5. The rolls 3 and 5 are weighted from the cantilever arm 15 through a fulcrum member 11 mounted in adjustably fixed position on weighting bar 7, set screw 13 being provided so that said fulcrum member may be adjusted along bar 7, such mechanism being the subject of E. C. Gwaltney et al., U. S. Patent No. 2,565,228, filed September 3, 1948. The cantilever arm 15 may be pressed down on fulcrum member 11 to weight said rolls 3 and 5, said arm having a spring 17 operating on one end thereof yieldingly to press said arm downwardly against said member as more fully explained in said U. S. Patent No. 2,525,647.

The overall draft is produced by the difference in speed of the delivery rolls 3 and 4 as compared to that of the holding rolls 5 and 6, and we prefer that such draft be in the neighborhood of 15 to 20, although the preferred embodiment of the drafting mechanism of our invention will produce drafts which range from 5 to 50. In order to maintain a firm bite on the sliver at each of these pairs of rolls, preferably the lower rolls 4 and 6 are finely fluted and machined accurately, and the upper rolls are covered with an elastic material, such as synthetic rubber, of sufficient firmness to cooperate with the lower rolls to produce a dependable continuously uniform bite but still having sufficient softness and elasticity to conform to variations in cross-sectional shape of the sliver being fed between them. More weight than that customarily used in drafting cotton should be applied to the top rolls 3 and 5 to prevent any appreciable slip between the sliver and the rolls. The

front roll 3, especially, should be heavily weighted.

The fiber control mechanism is located between the delivery rolls and the holding rolls and in general includes an endless sliver supporting apron 12, and, within the loop of said apron a positively driven apron supporting roll 14, and an apron bar assembly including an apron bar 16 and supporting means therefor mounted in adjustably fixed position between the apron supporting roll 14 and the delivery rolls 3 and 4, the apron being nipped to drive it between roll 14 and a driving roll 20 outside the loop of the apron. The apron 12 is further provided with an overlying positively driven apron roll 18 depressing the apron forwardly of apron supporting roll 14 and rotating with its adjacent surface moving in the same direction as apron 12 at a speed slightly higher than the apron to cooperate with the apron to control fibers passing through the drafting zone between the holding rolls 5 and 6 and the delivery rolls 3 and 4. Also, the roll 18, if driven faster than the apron, aids in driving the apron, said overlying roll normally being supported by means of and between the apron bar assembly and the apron supporting roll, as hereinafter more fully explained, to provide together with said apron a light frictional contact with the fibers of a sliver being drafted, and under normal conditions of operation not forming a nip either between overlying roll 18 and apron supporting roll 14, or between said overlying roll and apron bar 16, although being but slightly spaced from both to give as large a fiber control zone as possible. Such clearance permits the sliver to enter and leave the control zone without being gripped at either point, but rather it passes gradually into and from the control zone.

The sliver contacting surfaces of the overlying apron roll 18 may be of a number of materials, depending upon the nature of the fibers being drafted. We have found it desirable in most instances to employ a boss 19 of a resilient composition as shown in Fig. 12, such as natural or synthetic rubber of a durometer hardness, say from 50 to 100, though of course it will be understood that the hardness of the boss may vary within wide limits since the degree of grip required will vary with the nature of the fibers of the sliver and with the size of the sliver and the yarn to be spun from it. Such a boss is employed in conjunction with the usual endless apron of a somewhat resilient synthetic material of closely controlled uniform and predetermined thickness. In some instances a boss 21 of smooth steel is suitable, as shown in Fig. 13.

We have also employed a pin roll boss as shown in Figs. 10 and 11, in which the overlying apron contacting roll 18 is provided with a plurality of pins 60 extending outwardly from the peripheral surface of the roll 18. With such a pin roll, it is desirable to provide an enlarged end portion 62 on each end of the pin section, such end portion preferably being slightly larger in diameter than the outer diameter of the pin section and serving to contact the apron to keep it from contacting the pins and being damaged thereby. Such a roll apparently provides a limited combing action which is desirable for certain types of fibers and mixtures thereof.

The apron 12 is driven by apron supporting roll 14 and apron driving roll 20, the latter of which extends for substantially the entire length of the spinning or roving frame and is driven by suitable gearing located at the end thereof,

said driving roll 20 being located outside of the loop of the apron 12 beneath the apron supporting roll. The apron 12 is wrapped around the back of the apron supporting roll 14 in contact therewith for a substantial angular distance, well in excess of 90° as shown, and preferably for approximately 180°, is nipped to drive it between the apron supporting roll 14 and the apron driving roll 20, after passing over the front of apron driving roll 20 in contact therewith for a considerable angular distance around said roll—say about 90°—the two rolls 14 and 20 cooperating to drive the apron by frictional contact therewith. We have found that smooth metallic surfaces will serve for the apron contacting portions of rolls 14 and 20 and are entirely suitable for nipping the apron to drive it, though fluted or knurled surfaces could of course be used. An apron tensioning roll 22 is provided beneath apron driving roll 20 within the loop of apron 12 between said driving roll and apron bar 16 to properly tension said apron while still permitting a large driving contact with apron rolls 14 and 20 as above described, the apron moving directly from the tensioning roll to the apron driving roll 20. We prefer to employ a relatively low tension to said apron 12. The apron driving roll 20 additionally serves positively to drive the overlying apron roll 18 through apron supporting roll 14, said rolls being provided with suitable gearing for driving them as hereinafter more fully explained. The roll 18, if driven faster than the apron, thus aids in driving the apron by providing additional driving contact therewith, particularly since such roll is driven at a speed slightly greater than that of the apron.

The above arrangement provides the desirable uniform light frictional contact for the fibers of a sliver passing between the positively driven overlying roll 18 and the apron 12 even when the overlying roll is deeply depressed into the apron so as to provide the maximum control for the fibers of a sliver passing therethrough. Furthermore, since the apron rolls 14 and 20 drive the apron from immediately behind the sliver's first contact with the control mechanism and the overlying roll 18 is driven at a slightly higher speed than the apron, the apron is carried through the control zone around overlying roll 18 as well as being pulled by the tension roll 22 away from the apron bar end of said control zone. Such carrying action, we believe, tends to aid the passage of the apron around the overlying roll and provide a uniform and yielding pressure between the overlying roll and the apron.

In order to satisfy the practical, as well as the theoretical requirements of a drafting mechanism as hereinbefore set forth, we have provided a drafting mechanism which, even though its control mechanism be gear driven, may be easily and quickly adjusted to the optimum settings for the particular fiber or fibers to be drafted. Moreover, after such settings have once been made, our novel fiber control mechanism may be disassembled for cleaning or replacement of aprons without disturbing such settings, the various elements being so supported and arranged automatically to assume their prior settings when reassembled. Such disassembly and assembly, furthermore, does not require the use of any tools whatsoever.

To accomplish such results, the upper rolls of the control mechanism are all relatively short individually driven rolls so that it is not necessary to stop the entire frame in order to clean or re-

place elements of any one drafting mechanism. In our preferred embodiment, as best shown in Figs. 1 and 4, the upper rolls of the fiber control mechanism, apron supporting roll 14 and overlying apron roll 18, as well as apron bar 16, are made of a length sufficient to accommodate but four bosses (though more could be included), such a length being short enough to provide suitable gear drive for the said upper rolls, as well as to allow cleaning and replacement of elements without stopping the entire frame. A lesser number of bosses could of course be used, but at increased expense per spindle in the number of gears required and the attendant cleaning problems without achieving any real advantage. The upper delivery rolls 3 and upper holding rolls 5 are preferably of the usual two-boss type, as shown in U. S. Patent No. 2,525,647.

To support the relatively short four boss rolls 14 and 18 of the control mechanism, we provide roll stands 24 at the ends of such rolls, the roll stands in our preferred embodiment being attached to the spinning or roving frame at distances sufficient to accommodate four drafting elements. The roll stands 24 have tracks 25 on their upper surfaces, said tracks 25 serving adjustably to support from beneath each of the slides in which the various rolls and apron bars are supported, said slides including a lower delivery roll slide 26 for supporting the long lower delivery roll 4, a lower holding roll slide 28 for supporting the long lower holding roll 6, a slide 30 for supporting both the long apron driving roll 20 and the four boss apron rolls 14, and a slide 32 for supporting the short apron bars 16. The slides 28, 30, and 32 are all mounted in said tracks in adjustably fixed position by suitable bolts 33 extending through said slides and said tracks and being retained by nuts 35 bearing against the lower surface of said tracks so that the distances between the elements supported in said slides may be varied. Lower delivery roll slide 26 is fastened directly to stand 24 by a bolt 37 retained by a tapped hole in said stand. The slides 26 and 28 for the lower delivery and holding rolls respectively are of the customary type for rotatively supporting a roll extending through them and may be supplied with anti-friction bearings as is well known in the art. Slide 30 which supports the control mechanism rolls, as best shown in Figs. 1, 2, 5, 6, 7, and 8, includes a bearing 36 extending entirely therethrough for supporting the long apron driving roll 20. On either side of said slide 30 are provided downwardly extending slots 38 adapted to support and retain the short apron supporting rolls 14 and yet permit them to move toward and away from the driving roll 20, said slots extending from the upper portion of said slide into bearing 36. The web 39 of said slide between said slots serves to prevent endwise movement both of said rolls 14 and of the overlying rolls 18, suitable shoulders being provided on said web. By supporting both the driving roll 20 and the supporting roll 14 in a single slide at each end of an overlying roll 14, the essential parallelism of each of said overlying rolls with the driving roll 20 is maintained at all times to provide constant apron driving pressures at the bosses, as well as to insure proper tracking of the aprons.

The slide 32 provided for support of the apron bar 16, together called the apron bar assembly, as best shown in Figs. 8 and 9, has on either side thereof downwardly extending slots 40 to retain the apron bars 16 in a slanted position, said slots

extending from the upper surface of said slide for a distance determined by the position of said apron bars, while the surfaces 41 at the outer edges of said slide 32 adjoining said slots are slanted downwardly to form together with the surface of the apron bar a suitable angle for supporting the ends of overlying apron roll 18, as hereinafter more fully explained.

The four boss apron rolls 14 and 18 are gear-driven by long apron driving roll 20, said apron driving roll 20 having at one end thereof between each pair of roll stands 24 a gear 44, said gear 44 serving positively to drive each four boss apron supporting roll 14 through a mating gear 41 on said roll 14 at a speed preferably the same as that of apron driving roll 20. Each apron supporting roll 14 in turn positively drives its overlying apron roll 18 through a gear 42 on the opposite end of said supporting roll from said gear 41 and a mating gear 43 on overlying roll 18, and we prefer that the bosses 19 of the overlying roll 18 be driven at a peripheral speed of from about 3 to 6% more than that of said roll 14. In order to support apron supporting rolls 14 in slides 30, each of said rolls is provided with a pair of bearings 45 on gudgeons on the ends thereof, the non-rotating elements of said bearings 45 being retained near the bottom of slots 38 of slides 30 by the yielding contact of roll 14 with apron 12 which apron in turn rests on apron driving roll 20.

To obtain the drafts as hereinbefore set forth, the apron driving roll 20 is driven at a peripheral speed of from 1 to 3 times that of the lower holding roll 6, while the lower delivery roll 4 is driven at a peripheral speed of from 5 to 50 times the speed of the apron driving roll, such speeds being obtained by the usual gear-driving system at the end of the spinning or roving frame.

Overlying apron roll 18 is supported and spaced at the desired distance from the roll 14 by bearings 46 on gudgeons on the opposite ends thereof, the non-rotating elements of each of said bearings 46 being supported directly on and bridging between the slanted upper surface of the apron bar assembly and the stationary surface of the non-rotating element of a bearing 45 on apron supporting roll 14, such converging surfaces serving to support overlying roll 18 through its bearings 46 not only in regard to the pitch diameter of gears 42 and 43, but also with reference to the apron bar 16 and the apron supporting roll 14 to maintain said overlying roll normally slightly spaced at a uniform distance from said apron supporting roll and apron bar so as not to nip the apron at either, and to provide the desired light frictional contact for a sliver passing through the control zone of our control mechanism. It is contemplated, however, that under some conditions it may be desirable to nip apron 12 between rolls 18 and 14 either with or without a positively driven overlying roll, the sliver in such case being nipped between overlying roll 18 and apron 12, to give a two zone drafting system, and under such circumstances the bearing 46 would not necessarily fix the normal spacing between rolls 14 and 18, although it would so operate between roll 18 and apron bar 16. The bearings 45 and 46 on apron supporting roll 14 and overlying apron roll 18, though preferably of the anti-friction type, may be of any material having low frictional characteristics, such materials as, for example, nylon or sintered metal being suitable. With either type of bearing, the outer surface of the non-rotating bearing element is preferably

cylindrical to permit the bearing to roll along its supporting surfaces during adjustment of the apparatus, as hereinafter more fully explained.

Springs 48 are arranged on slides 30 at each end of rolls 18 to bear downwardly on the non-rotating element of bearings 46 to urge overlying roll 18 firmly downwardly against the opposing supporting bearing surfaces 45 on apron supporting roll 14 and the apron bar assembly. A shoulder 49 is provided in post 50 on slide 30 for retaining said spring in a raised inoperative position out of contact with said bearings when so desired. The spring 48 also serves to provide the apron nipping pressure between apron supporting roll 14 and driving roll 20, aprons of proper predetermined and uniform thickness being employed to maintain approximately correct relation of the pitch circles of gears 40 and 41. The overlying rolls 18 and the apron supporting rolls 14 are all supported by the driving rolls 20 in a floating relationship with said roll, the spacing of an overlying roll 18 from a roll 14 being maintained as above described while the two rolls 14 and 18 as a group are permitted to float to provide suitable yielding apron nipping pressure between said rolls 14 and 20, the apron nipping pressure being applied by springs 48 to overlying roll 18, such pressure of the spring being supplemented by the weight of said rolls 18 and 14. Thus springs 48, since they need not supply the entire pressure, may be relatively small and light.

In order to adjust the drafting mechanism of our invention, the slides 28, 30 and 32 may be moved along the track 25 on roll stands 24. During such adjustment, for example, it is usual to retain the lower delivery roll slide 26 in fixed position together with its upper roll 3 and vary the spacing from the delivery rolls 3 and 4 to the holding rolls 5 and 6, such spacing generally being somewhat greater than the longest length of fiber to be drafted. In such case, of course, the holding rolls 5 and 6 will be adjusted as a unit so that they will at all times form a sliver nipping contact. Since the novel control mechanism portion of the drafting mechanism is provided with two slides instead of the usual one, i.e. the apron bar slide 32 and roll slide 30, its flexibility and ease of adjustment is greatly increased, since not only may the distance of the overlying apron roll 18 from the delivery rolls 3 and 4 and the holding rolls 5 and 6 be varied at will, but the amount of control of said mechanism may be varied simply by varying the distance between slides 30 and slides 32, since the overlying apron roll 18 bridges between the converging surfaces of the apron bar assembly and the non-rotating bearing elements of apron supporting roll 14 and thus is in effect supported by each of said slides. Hence the vertical level of the overlying roll is fixed by the horizontal spacing therebetween. For instance, if it is desired to increase the amount of control by depressing overlying roll 18 deeper into apron 12, the spacing between slide 30 and slide 32 is increased by loosening bolts 33, moving slides 30 and 32 further apart on track 25, and re-tightening bolts 33. In such case, overlying apron roll 18, being supported through its bearings 46 bridging between the slanted surface of the apron bar assembly and the apron supporting roll 14 through the bearing 45 thereof will be pressed downwardly by spring 48 further into the depressed curve of the apron 12 since the normally non-rotating element of bearing 45 will have rolled down the slanted surface

of the apron bar assembly until stopped by contact with the non-rotating element of bearing 45 on apron supporting roll 14. If less control is desired, the movement of said slides 30 and 32 toward one another will raise roll 18 by rolling bearing 46 up the slanted surface of said apron bar assembly by contact with bearing 45 and thus decrease the wrap of the apron 12 around said roll. If it is desired to draft extremely short fibers with our novel drafting mechanism, overlying roll 18 may be depressed into the apron to any desired extent with holding roll 5 adjusted (by releasing set screw 10 and moving roll bearing 9 forward) to a position overlying apron supporting roll 14 to nip apron 12 between said rolls 5 and 14. Under such circumstances, lower holding roll 6 is not used, rolls 5 and 14 operating as the holding rolls, and the control zone between overlying roll 18 and apron 12 begins close to the nip of the holding rolls 5 and 14. Also, fulcrum member 11 on bar 7 must be moved forward along bar 7 out of the way of upper holding roll bearing 9.

Thus the adjustment of the amount and kind of control is extremely simple and the predetermined spacing between overlying roll 18 and apron supporting roll 14 and between overlying roll 18 and the apron bar assembly to produce the desired light frictional grip on the sliver passing therethrough will be at all times maintained constant in spite of the wrap of the apron 12 around said roll.

With the elements of our novel control mechanism arranged as above described, it will be seen that in order to disassemble each four boss portion of our novel control mechanism it is only necessary to release opposite springs 48 by raising them upward where they may be retained by shoulder 49, pick up overlying apron roll 18 from the apron 12, detach the four aprons 12 from the apron tensioning rolls 22, and then together slide apron bar 32 and apron supporting roll 14 out of their respective slots 40 and 38 in slides 32 and 30, the aprons 12 being simultaneously removed since they encircle apron bar 16 and apron supporting roll 14. The aprons 12 may then be removed endwise from the supporting roll 14 and apron bar 16 for replacement or cleaning, and the disassembled rolls and their gears may be readily cleaned. To assemble the control mechanism it is merely necessary to place the four aprons 12 over the apron bar 16 and apron supporting roll 14, drop the apron bar 16 and supporting roll 14 into their respective slots 40 and 38 on slides 32 and 30, re-engage the aprons 12 with the apron tensioning rolls 22 and place the overlying apron roll 18 in position on top of the apron 12. Springs 48 may then be released from shoulders 49 to provide the downward pressure for rolls 18 and 14. Since the adjustment of roll 14 is determined by slots 38 on slides 30 and by the apron 12 and the roll 20 and the slides were not moved during the disassembly and assembly as above described, the roll 14 will automatically return to its previously set position. Likewise, since the setting of roll 18 is determined in one direction by the apron supporting roll 14 and in another direction by the apron bar assembly, the roll 18 will also automatically return to its previously set position, since the apron bar slide 32 was not moved during the disassembly and assembly and the slots 40 on said slide will retain the apron bar 16 in the same position relatively thereto.

Such an arrangement likewise makes easy the

11

changing of the overlying apron roll 18 to conform with the drafting requirements of a particular type of sliver. Thus sets of rolls 18 having the various types of bosses as hereinbefore described may be kept on hand so that the most desirable type of boss for the particular type of fiber to be drafted may be used.

Thus it will be seen that we have provided a drafting mechanism having a degree of control and a flexibility not before achieved, such drafting mechanism being capable of drafting an extremely wide range of fibers and mixtures thereof and properly controlling all of such fibers during such drafting. It will be further seen that the drafting mechanism thus provided satisfies the practical requirements of easy adjustability and rapid disassembly for cleaning to an extent never before realized. Various modifications of the novel mechanism within the spirit of our invention and the scope of the appended claims will be apparent to those skilled in the drafting art.

We claim:

1. A drafting mechanism of the character described having a drafting zone comprising a pair of delivery rolls at the forward end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which said sliver is drawn by said delivery rolls, said control mechanism including an endless looped underlying sliver supporting apron, a positively driven apron supporting roll within the loop of and in contact with said apron for supporting and driving said apron, slide means supporting said apron supporting roll, an apron bar assembly including an apron bar and supporting slide means therefor, said apron bar being within the loop of said apron in contact with said apron, track means supporting said apron supporting roll slide and said apron bar slide in adjustably fixed position for adjustment of each of said slides to vary the horizontal spacing of said apron bar and said apron supporting roll from each other as well as independently to vary the horizontal spacing of either said roll or said apron bar from said delivery rolls, and an overlying apron roll outside the loop of and depressing said apron forwardly of said apron supporting roll, said overlying roll being supported for rotation with its vertical level adjustably fixed by the horizontal spacing between said apron bar slide means and said apron supporting roll slide means.

2. A drafting mechanism of the character described having a drafting zone comprising a pair of delivery rolls at the forward end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which said sliver is drawn by said delivery rolls, said control mechanism including an endless looped underlying sliver supporting apron, a positively driven apron supporting roll within the loop of and in contact with said apron for supporting and driving said apron, slide means

12

supporting said apron supporting roll, an apron bar assembly including an apron bar and supporting slide means therefor, said apron bar being within the loop of said apron in contact with said apron, track means supporting said apron supporting roll slide and said apron bar slide in adjustably fixed position for adjustment of each of said slides to vary the horizontal spacing of said apron bar and said apron supporting roll from each other as well as independently to vary the horizontal spacing of either said roll or said apron bar from said delivery rolls, and an overlying apron roll outside the loop of and depressing said apron forwardly of said apron supporting roll, said overlying roll being supported for rotation by means of said apron bar assembly and said apron supporting roll with its vertical level adjustably fixed by the horizontal spacing therebetween.

3. A drafting mechanism of the character described having a drafting zone comprising a pair of delivery rolls at the forward end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which said sliver is drawn by said delivery rolls, said control mechanism including an endless looped underlying sliver supporting apron, a positively driven apron supporting roll having bearing means thereon, said roll being within the loop of and in contact with said apron for supporting and driving said apron, slide means supporting said apron supporting roll, an apron bar assembly including an apron bar and supporting slide means therefor, said apron bar being within the loop of said apron in contact with said apron, track means supporting said apron supporting roll slide and said apron bar slide in adjustably fixed position for adjustment of each of said slides to vary the horizontal spacing of said apron bar and said apron supporting roll from each other as well as independently to vary the horizontal spacing of either said roll or said apron bar from said delivery rolls, and an overlying apron roll having bearing means thereon, said roll being outside the loop of and depressing said apron forwardly of said apron supporting roll, said overlying roll being supported through its bearing means by contact of said means with said apron bar assembly and said apron supporting roll bearing means with its vertical level adjustably fixed by the horizontal spacing between said slides.

4. A drafting mechanism as claimed in claim 3, further having spring means contacting said overlying roll bearing means to urge said overlying roll downwardly to maintain contact of said bearing means with said apron bar assembly and the apron supporting roll bearing means.

5. A drafting mechanism of the character described having a drafting zone comprising a pair of delivery rolls at one end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which

said sliver is drawn by said delivery rolls, said control mechanism including an endless looped underlying sliver supporting apron, an apron supporting roll partially encircled within a rearward loop of and in contact with said apron for an angular distance in excess of 90°, a positively driven apron driving roll outside and below the said rearward loop of said apron in contact with said apron immediately in advance of and guiding it to said loop and forming with said apron supporting roll an apron driving nip for driving said apron, an apron bar within the loop of said apron in contact with said apron, and an overlying positively driven apron roll outside the loop of and depressing said apron forwardly of said apron supporting roll.

6. A drafting mechanism of the character described having a drafting zone comprising a pair of delivery rolls at one end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which said sliver is drawn by said delivery rolls, said control mechanism including an endless looped underlying sliver supporting apron, an apron supporting roll partially encircled within a rearward loop of and in contact with said apron for an angular distance in excess of 90°, a positively driven apron driving roll outside and below the said rearward loop of said apron in contact with said apron immediately in advance of and guiding it to said loop and forming with said apron supporting roll an apron driving nip for driving said apron, slide means rotatively supporting said driving roll, and means supporting said apron supporting roll for movement toward and away from said apron driving roll to form a yielding apron driving nip therebetween, an apron bar within a forward loop of said apron in contact with said apron, and an overlying apron roll outside the loop of and depressing said apron forwardly of said apron supporting roll.

7. A drafting mechanism of the character described having a drafting zone comprising a pair of delivery rolls at one end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which said sliver is drawn by said delivery rolls, said control mechanism including an endless looped underlying sliver supporting apron, an apron supporting roll partially encircled within a rearward loop of and in contact with said apron for an angular distance in excess of 90°, a positively driven apron driving roll outside and below the said rearward loop of said apron in contact with said apron immediately in advance of and guiding it to said loop and forming with said apron supporting roll an apron driving nip for driving said apron, an overlying positively driven apron roll outside the loop of and depressing said apron forwardly of said apron supporting roll, means rotatively supporting said apron supporting roll for movement toward and away from said apron driving roll to form a yielding apron driving nip therebetween,

and an apron bar within said apron in contact with said apron.

8. A drafting mechanism of the character described having a drafting zone comprising a pair of delivery rolls at one end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which said sliver is drawn by said delivery rolls, said control mechanism including an endless looped underlying sliver supporting apron, an apron bar within the loop of said apron in contact with said apron, a positively driven apron supporting roll partially encircled within a rearward loop of and in contact with said apron for an angular distance in excess of 90°, a positively driven apron driving roll outside and below the said rearward loop of said apron in contact with said apron immediately in advance of and guiding it to said loop and cooperating with said apron supporting roll to drive said apron, gears for positively driving said apron supporting roll from said apron driving roll, an overlying positively driven apron roll supported for rotation outside the loop of and depressing said apron forwardly of said apron supporting roll, and gears for driving said overlying apron roll from said apron supporting roll.

9. A drafting mechanism of the character described having a drafting zone comprising a pair of delivery rolls at one end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which said sliver is drawn by said delivery rolls, said control mechanism including an endless looped underlying sliver supporting apron, an apron bar within the loop of said apron in contact with said apron, a positively driven apron supporting roll partially encircled within a rearward loop of and in contact with said apron for an angular distance in excess of 90°, a positively driven apron driving roll outside and below the said rearward loop of said apron in contact with said apron immediately in advance of and guiding it to said loop and cooperating with said apron supporting roll to drive said apron, means rotatively supporting said apron supporting roll for movement toward and away from said apron driving roll, gears for positively driving said apron supporting roll from said apron driving roll, an overlying positively driven apron roll supported for rotation outside the loop of and depressing said apron forwardly of said apron supporting roll, and gears for driving said overlying apron roll from said apron supporting roll.

10. A drafting mechanism of the character described having a drafting zone comprising a pair of delivery rolls at one end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted be-

tween said pairs of rolls and through which said sliver is drawn by said delivery rolls, said control mechanism including an endless looped underlying sliver supporting apron, an apron bar within the loop of said apron in contact with said apron, a positively driven apron supporting roll having bearing means thereon, said roll being partially encircled within a rearward loop of and in contact with said apron for an angular distance in excess of 90°, a positively driven apron driving roll outside and below the said rearward loop of said apron in contact with said apron immediately in advance of and guiding it to said loop and forming with said apron supporting roll an apron driving nip for driving said apron, gears on said apron supporting roll and said apron driving roll for driving said supporting roll from said driving roll, means supporting said supporting roll bearing means for movement toward and away from said apron driving roll, an overlying positively driven apron roll having bearing means thereon, said roll being outside the loop of and depressing said apron forwardly of said apron supporting roll, said roll being supported at a uniform distance from said apron supporting roll by contact of the bearing elements of said overlying roll and said apron supporting roll, gears on said overlying roll and said apron supporting roll for driving said overlying apron roll from said apron driving roll, and means acting on said overlying roll urging said overlying roll and said apron supporting roll downwardly toward said apron driving roll to nip said apron between said apron supporting and driving rolls and to provide a substantially uniform clearance between said gears.

11. A drafting mechanism of the character described having a drafting zone comprising a pair of delivery rolls at one end and a pair of holding rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which said sliver is drawn by said delivery rolls, said control mechanism including an endless looped underlying sliver supporting apron, an apron bar assembly including an apron bar and supporting means therefor within the loop of said apron in contact with said apron, a positively driven apron driving roll outside and below a rearward loop of said apron in contact with said apron immediately in advance of and guiding it to said loop, a positively driven apron supporting roll partially encircled within said rearward loop of and in contact with said apron for an angular distance in excess of 90° and, forming with said apron driving roll an apron driving nip for driving said apron, said supporting roll being supported by said driving roll, gears for driving said supporting roll from said driving roll, an overlying positively driven apron roll outside the loop of and depressing said apron forwardly of said apron supporting roll, said roll being supported for rotation by means of said apron bar assembly and said apron supporting roll with its vertical level adjustably fixed by the horizontal spacing therebetween, and gears for driving said overlying apron roll from said apron driving roll.

12. A drafting mechanism of the character described having a drafting zone comprising a pair of delivery rolls at one end and a pair of holding

rolls at its opposite end, means supporting said rolls to act simultaneously on portions of a sliver spaced apart by a distance greater than the average fiber length of the sliver to feed and draft it, mechanism for revolving said rolls at the speeds necessary to produce the desired draft, and a rotary fiber control mechanism mounted between said pairs of rolls and through which said sliver is drawn by said delivery rolls, said control mechanism including an endless looped underlying sliver supporting apron, an apron bar assembly including an apron bar and supporting means therefor within the loop of said apron in contact with said apron, a positively driven apron driving roll outside and below a rearward loop of said apron in contact with said apron immediately in advance of and guiding it to said loop, a positively driven apron supporting roll having bearing means thereon said roll being partially encircled within the said rearward loop of and in contact with said apron for an angular distance in excess of 90° and, forming with said apron driving roll an apron driving nip for driving said apron, gears for driving said supporting roll from said driving roll, an overlying positively driven apron roll having bearing means thereon, said roll being outside the loop of and depressing said apron forwardly of said apron supporting roll, said roll being supported for rotation by means of contact of the bearing elements of said overlying roll with the bearing elements of said apron supporting roll, and with the vertical level of said overlying apron roll adjustably fixed by the horizontal spacing between said apron bar assembly and said apron supporting roll, and gears on said overlying roll and said apron supporting roll for driving said overlying apron roll from said apron driving roll.

13. A drafting mechanism as claimed in claim 12 including means acting on said overlying roll urging said overlying roll and said apron supporting roll downwardly toward said apron driving roll to nip said apron between said apron supporting roll and said apron driving roll.

14. A drafting mechanism as claimed in claim 13 in which said means acting on said overlying roll includes spring means in contact with the bearing elements on said overlying roll.

15. A drafting mechanism comprising a pair of delivery rolls at the forward end and a pair of holding rolls at its opposite end with a rotary fiber control mechanism therebetween, said control mechanism including an endless looped underlying sliver supporting apron and a positively driven apron supporting roll within the loop of and in contact with said apron for supporting and driving said apron, slide means supporting said apron supporting roll, an apron bar assembly including an apron bar and supporting slide means therefor, said apron bar being within the loop of said apron in contact with said apron, track means supporting said apron supporting roll slide and said apron bar slide in adjustably fixed position for adjustment of each of said slides to vary the horizontal spacing of said apron bar and said apron supporting roll from each other as well as independently to vary the horizontal spacing of either said roll or said apron bar from said delivery rolls, and an overlying apron roll outside the loop of and contacting said apron adjacent said apron supporting rolls.

16. A drafting mechanism comprising a pair of weighted delivery rolls at the forward end and a rotary fiber control mechanism mounted rear-

wardly thereof, said control mechanism including an endless looped underlying sliver-supporting apron and an externally weighted readily removable apron-supporting roll within the loop of and in contact with said apron for supporting and driving said apron, slide means supporting said apron-supporting roll for yieldable apron-nipping vertical movement, a positively driven apron-driving roll partially encircled by and feeding said apron to said apron supporting roll and cooperating therewith to nip and drive said apron, an apron bar assembly including an apron bar and supporting means therefor, said apron bar being within the loop of said apron in contact with said apron near said delivery rolls, a base supporting said apron supporting roll slide in adjustably fixed position for adjustment to vary the horizontal spacing of said apron bar and said apron supporting roll from each other as well as to vary the horizontal spacing of said apron-supporting roll from said delivery rolls, and an overlying apron roll outside the loop of and contacting said apron to press sliver down upon said apron adjacent said apron supporting roll.

17. A drafting mechanism as claimed in claim 16 in which said overlying apron roll is yieldably weighted by weighting means carried by said slide means supporting said apron-supporting roll.

18. A drafting mechanism of the character described having a drafting zone greater in length than the average fiber length of the sliver with a pair of delivery rolls at the forward end of said zone, mechanism for revolving said rolls at a speed necessary to produce the desired draft, a rotary fiber control mechanism mounted rearwardly of said delivery rolls and from which said sliver is drawn by said delivery rolls, said control mechanism including an endless looped underlying sliver-supporting apron, an apron bar within a forward portion of the loop of and in contact with said apron adjacent said delivery rolls, a yieldably mounted readily removable apron-supporting roll partially encircled within a rearward portion of the loop and in contact with said apron for an angular distance in excess of 90°, a positively driven apron-driving roll outside and below the said rearward portion of the loop of the said apron in contact with said apron immediately in advance of and guiding it to said loop portion and cooperating with said apron-supporting roll to drive said apron, an apron-tensioning roll tensioning and contacting said apron between said apron bar and said apron driving roll, base-supported mounting means for said apron supporting and apron driving rolls, said means rotatively supporting said apron supporting roll for movement toward and away from said apron driving roll to yieldably nip the apron therebetween, and an overlying apron-contacting roll supported for rotation outside the loop of and in contact with the upper surface of said apron for pressing the sliver downwardly into engagement with said apron.

19. A drafting mechanism as claimed in claim 18 wherein said overlying apron-contacting roll is mounted, weighted, and arranged to nip the apron between it and said apron-supporting roll.

20. A drafting mechanism of the character described having a drafting zone greater in length than the average fiber length of the sliver with a pair of weighted delivery rolls at the forward end of said zone, mechanism for revolving said rolls at a speed necessary to produce the desired draft, a rotary fiber control mechanism mounted rearwardly of said delivery rolls and from which

said sliver is drawn by said delivery rolls, said control mechanism including an endless looped underlying sliver-supporting apron, an apron bar within a forward portion of the loop of and in contact with said apron adjacent said delivery rolls, a yieldably mounted readily removable apron supporting roll partially encircled within a rearward portion of the loop of and in contact with said apron for an angular distance in excess of 90°, a positively driven apron driving roll outside and below the said rearward portion of the loop of the said apron in contact with said apron immediately in advance of and guiding it to said loop portion and cooperating with said apron supporting roll to drive said apron, an apron-tensioning roll tensioning and contacting said apron between said apron bar and said apron driving roll, a base-supported mounting means for said apron supporting and apron driving rolls, said means rotatively supporting said apron supporting roll for movement toward and away from said apron driving roll to yieldably nip the apron therebetween, releasable weighting means pressing downwardly said apron-supporting roll for normally maintaining the said nip of said apron, and an overlying apron-contacting means outside the loop of and in contact with the upper surface of said apron for pressing the sliver downwardly into engagement with said apron.

21. A drafting mechanism as claimed in claim 20 wherein there is provided a pair of weighted rear feed rolls and said overlying apron-contacting means is mounted, weighted, and arranged to nip the apron between it and said apron supporting roll to provide two thus separated drafting zones.

22. A drafting mechanism comprising a pair of delivery rolls at the forward end and a pair of holding rolls at its opposite end with a rotary fiber control mechanism therebetween, said control mechanism including an endless looped underlying sliver supporting apron and an apron supporting roll within the loop of and in contact with said apron for supporting said apron, slide means supporting said apron supporting roll, an apron bar assembly positioned between said apron supporting roll and said delivery rolls, said assembly including an apron bar and supporting means therefor, said apron bar being within the loop of said apron in contact with said apron, track means supporting said apron supporting roll slide in adjustably fixed position for adjustment of said slide to vary the horizontal spacing between said apron bar and said apron supporting roll as well as to vary the horizontal spacing of said apron supporting roll from said delivery rolls, and an overlying apron roll outside the loop of and contacting said apron to press sliver down upon said apron adjacent said apron supporting roll, said overlying roll being supported by said apron bar assembly and said apron supporting roll, said overlying roll being vertically adjustable solely by the horizontal spacing between said apron bar assembly and said apron supporting roll.

23. A drafting mechanism comprising a pair of delivery rolls at the forward end and a pair of holding rolls at its opposite end with a rotary fiber control mechanism therebetween, said control mechanism including an endless looped underlying silver supporting apron and an apron supporting roll within the loop of and in contact with said apron for supporting said apron, slide means supporting said apron supporting roll, an apron bar assembly positioned between said

apron supporting roll and said delivery rolls, said assembly including an apron bar and supporting means therefor with said assembly presenting a downwardly and rearwardly slanted surface converging downwardly with a surface of said apron supporting roll, said apron bar being within the loop of said apron in contact with said apron, track means supporting said apron supporting roll slide in adjustably fixed position for adjustment of said slide to vary the horizontal spacing between said apron bar and said apron supporting roll as well as to vary the horizontal spacing of said apron supporting roll from said delivery rolls, and an overlying apron roll outside the loop of and contacting said apron to press sliver down upon said apron adjacent said apron supporting roll, said overlying roll being supported by the converging slanted surfaces of said apron bar assembly and said apron supporting roll, said overlying roll being vertically adjustable solely by the horizontal spacing between said apron bar assembly and said supporting roll.

24. A drafting mechanism comprising a pair of delivery rolls at the forward end and a pair of holding rolls at its opposite end with a rotary fiber control mechanism therebetween, said control mechanism including an endless looped underlying sliver supporting apron and an apron supporting roll having bearing means thereon, said roll being within the loop of and in contact with said apron for supporting said apron, slide means supporting said apron supporting roll, an apron bar assembly positioned between said apron supporting roll and said delivery rolls, said assembly including an apron bar and supporting means therefor with said assembly presenting a downwardly and rearwardly slanted surface con-

verging downwardly with the surface of said apron supporting roll bearing means, said apron bar being within the loop of said apron in contact with said apron, track means supporting said apron supporting roll slide in adjustably fixed position for adjustment of said slide to vary the horizontal spacing between said apron bar and said apron supporting roll as well as to vary the horizontal spacing of said apron supporting roll from said delivery rolls, and an overlying apron roll having bearing means thereon, said roll being outside the loop of and contacting said apron to press sliver down upon said apron adjacent said apron supporting roll, said overlying roll being supported by contact of its bearing means with the converging slanted surfaces of said apron bar assembly and said apron supporting roll bearing means, said overlying roll being vertically adjustable solely by the horizontal spacing between said apron bar assembly and said supporting roll bearing means.
